F. STRUCHEN

METHOD OF SPINNING STEPPED FLANGES AND APPARATUS THEREFOR

Filed April 7, 1924

UNITED STATES PATENT OFFICE.

FRED STRUCHEN, OF ERIE, PENNSYLVANIA.

METHOD OF SPINNING STEPPED FLANGES AND APPARATUS THEREFOR.

Application filed April 7, 1924. Serial No. 704,895.

To all whom it may concern:

Be it known that I, FRED STRUCHEN, a citizen of the United States, residing at Erie, in the county of Erie and State of Pennsylvania, have invented new and useful Improvements in Methods of Spinning Stepped Flanges and Apparatus Therefor, of which the following is a specification.

The invention is designed to facilitate the forming of receptacles having stepped flanges. Ordinarily this is accomplished by a stamping operation, the initial flange being formed in one stamping operation and the stepped flange being formed in a subsequent operation. Ordinarily the flange is then trimmed and beaded by a spinning operation.

With my method and apparatus one flange is formed by stamping with the receptacle and the stepped flange is formed by spinning so that the trimming, offset flanging and beading may be done in a sequence of operations on the spinning machine, thus reducing the operations and the time and expense in forming such offset flanges. Features and details of the invention will appear from the specification and claims.

The apparatus forming the subject-matter of the invention and by which the method may be practiced is shown in the accompanying drawings as follows:

Fig. 1 shows a plan view of the spinning machine.

Fig. 2 a cross section.

Fig. 3 a sectional view in perspective of the flanged receptacle as it comes from a stamping operation.

Fig. 4 a sectional view in perspective of the receptacle formed with the stepped flange.

Fig. 5 a sectional view in perspective of the completed article.

Fig. 6 a plan view of the flange deflecting tool.

Fig. 7 a side elevation of the same.

Fig. 8 an end view of the tool.

1 marks the bed of the machine, 2 the spinning head spindle, 3 the spinning head, 4 the flanged article as it comes from the stamping operation and as it is placed on the head, 5 the follower plate for holding the article on the spinning head, 6 the tail spindle for holding the head 5 in place. This apparatus is common with spinning tools.

55 A tool holding base 7 is mounted on the

frame 1 and a swinging tool frame 8 is mounted on a pin 9 carried by the base 7. A lever 10 is fulcrumed on a pin 11 on the base 7 and has a pin and slot connection with the frame 8 whereby the frame may be swung to bring the tools into operative position with the flange.

Cutting disks 13 are mounted on a post 13^a at the rear end of the frame 8 and are brought into cutting position with relation 65 to the flange 4^a in the initial operation on the machine. This trimming is very rapidly done by these disks—in fact, completed practically in a single rotation. The stepped flange forming tool is then thrown into operation. It comprises a tool 14 pivotally mounted on a pin 15, the pin being carried by a bracket 15^a on an adjustable base 15^b. The base 15^b is adjustably mounted. The tool base 7 is adjustably mounted on the frame 8. The tool 14 is adapted to be swung by a lever 16, this lever being mounted on a pin 17. The pin 17 is secured in a post 18 and the lever is connected with the tool 14 by a pin and slot connection 19. By pulling 80 the lever up with the frame in the position shown in Fig. 8 the front end of the tool is swung up into position to operate on the flange 4.

After the forming of the stepped flange a 85 bead is formed on the stepped flange by means of a beading wheel 20 mounted on the post 18. This is swung into operation as the tool 14 drops back from engaging position by throwing the end of the lever 10 downwardly.

The effect of the stepped flanging tool on the flange 4 is to form an offset step 21 with a flange 22 extending outwardly from the stepped portion 21, these parts being formed 95 of the metal previously in the flange 4. The edge of the flange is beaded forming a bead 23 as shown in Fig. 5 by the beaded wheel 20.

The stepped flange forming tool is shown 100 in detail in Figs. 6, 7 and 8. It has the camming and deflecting surface 24 which engages the edge of the flange 4^a, crowds it over to the offset position, and into a slit 25 which straightens up the deflected portion 105 of metal to the plane of the final flange 22 and the end of the tool operating against the intervening metal between the base of the flange 4^a and the metal of the flange 22 forms the step 21 through the spinning ac- 110

tion of these two surfaces. This tool spins down the metal very rapidly and leaves a finished edge.

What I claim as new is:—

5. The method of forming stepped flanged cylinders, which consists in rotating a flanged cylinder, spinning the flange and step by engaging opposite sides of the flange and deflecting the flange sidewise through the action of a camming and deflecting surface forced into spinning relation by a thrust exerted in a direction at right angles to the axis of the cylinder. 10

2. The method of forming stepped flanged cylinders, which consists in rotating a flanged cylinder, trimming the flange while so rotated, spinning the flange and step by engaging opposite sides of the flange and deflecting the flange sidewise through the action of a camming and deflecting surface forced into spinning relation by a thrust exerted in a direction at right angles to the axis of the cylinder, said trimming and spinning operations being successive but 15 with a continuous rotation of the cylinder. 20

3. In a spinning machine, the combination of a head, a flange deflecting and spinning tool in operative relation to the head and having a flange receiving slit having walls adapted to engage opposing surfaces of a flange, and a flange deflecting surface leading to the slit and a step forming face leading from the slit. 25

4. In a spinning machine, the combination of a head, a flange deflecting and spinning tool in operative relation to the head and having a flange receiving slit having 30

5. In a spinning machine, the combination of a head, a flange deflecting and spinning tool in operative relation to the head and having a flange receiving slit, having walls adapted to engage opposing surfaces of a flange, a flange deflecting surface leading to the slit and a step forming face leading from the slit, and means for moving the tool toward and from the head. 45

6. In a spinning machine, the combination of a head, a cutter for cutting a flanged cylinder mounted on the head, a flange spinning tool in operative relation to the head having a flange receiving slit having walls adapted to engage opposing surfaces of a flange, and a flange deflecting surface leading to the slit and a step forming face leading from the slit. 50

7. In a spinning machine, the combination of a head, a cutter for cutting a flanged cylinder mounted on the head, a flange spinning tool in operative relation to the head having a flange receiving slit having walls adapted to engage opposing surfaces of a flange, a flange deflecting surface leading to the slit and a step forming face leading from the slit, and means operating the cutter and step flange forming tool in sequence. 55

In testimony whereof I have hereunto set my hand.

FRED STRUCHEN.

walls adapted to engage opposing surfaces of a flange, a flange deflecting surface leading to the slit and a step forming face leading from the slit, and means for moving the tool toward and from the head. 40

5. In a spinning machine, the combination of a head, a flange deflecting and spinning tool in operative relation to the head and having a flange receiving slit, having walls adapted to engage opposing surfaces of a flange, a flange deflecting surface leading to the slit and a step forming face leading from the slit, and means for moving the tool toward and from the head comprising a swinging mounting; 45 50

6. In a spinning machine, the combination of a head, a cutter for cutting a flanged cylinder mounted on the head, a flange spinning tool in operative relation to the head having a flange receiving slit having walls adapted to engage opposing surfaces of a flange, and a flange deflecting surface leading to the slit and a step forming face leading from the slit. 55 60

7. In a spinning machine, the combination of a head, a cutter for cutting a flanged cylinder mounted on the head, a flange spinning tool in operative relation to the head having a flange receiving slit having walls adapted to engage opposing surfaces of a flange, a flange deflecting surface leading to the slit and a step forming face leading from the slit, and means operating the cutter and step flange forming tool in sequence. 70

In testimony whereof I have hereunto set
my hand.

FRED STRUCHEN.
